[57] **CLAIM**

The ornamental design for a display screen with dialog box, as shown and described.

DESCRIPTION

FIG. 1 is a front view of a display screen with a computer dialog box;

FIG. 2 is a front view thereof, the computer dialog box is shown separately for clarity of illustration;

FIG. 3 is a front view of a second embodiment thereof;

FIG. 4 is a front view of the second embodiment shown in FIG. 3, the dialog box is shown separately for clarity of illustration;

FIG. 5 is a front view of a third embodiment thereof;

FIG. 6 is a front view of a fourth embodiment thereof;

FIG. 7 is a front view of the first embodiment shown in FIGS. 1 and 2, on an enlarged scale, with the dialog box shown separately for clarity of illustration;

FIG. 8 is as front view of the second embodiment shown in FIGS. 3 and 4, on an enlarged scale, with the dialog box shown separately for clarity of illustration;

FIG. 9 is a front view of a fifth embodiment thereof; and, FIG. 10 is as front view of a sixth embodiment thereof.

The surface indicia in the form of text, indicated by broken lines in FIGS. 3, 4, 6, 8, and 10, is merely exemplary of any lettering that could be applied to the design and forms no part of the claimed design.

The broken line description of text is FIGS. 3, 4, 6, 8, and 10 in for illustrative purposes only and forms no part of the claimed design.
